FISH TAIL PROPELLER

Harry Clayton Martin, St. Petersburg, Fla.

Application January 15, 1937, Serial No. 120,812

17 Claims. (Cl. 115—30)

My invention relates to propellers for boats and particularly to that type used to propel and steer small boats by hand.

Primarily my invention has for its object to provide a portable hand propeller which may be folded and carried in a small space and yet one which is easily mounted on a boat for use. Further it is an object of the invention to provide a device which propels the boat and at the same time serves as a tiller and which accomplishes both purposes with a minimum loss of effort.

Still further it is an object of the invention to provide a device with all of the above mentioned features and also with a simplified means for reversing the propeller blade when it becomes necessary to backwater.

Other objects will in part be obvious and in part generally pointed out hereinafter.

To the attainment of the aforesaid objects and ends, the invention still further resides in those novel details of construction, combination and arrangement of parts, all of which will be first fully described in the following detailed description, then be pointed out in the appended claims, references being had to the accompanying drawings, in which:

Fig. 1 is a side elevation showing the device mounted on the stern of a boat, a portion of the stern of a boat being shown in section.

Fig. 2 is a detail elevational view of the coupling plate which carries the eye bolts and wing nuts.

Fig. 3 is a detail elevational view of the face of the coupling plate which is slotted.

Fig. 4 is a detail view showing some of the more important structures in cross section.

Fig. 5 is a detail side elevation showing a modified form of the propeller blade.

Fig. 6 is a top plan view of the reversing and stroke checking mechanism.

Fig. 7 is a detail sectional view of the stud 33 showing the lubricating duct.

In the drawing in which like numerals of reference designate like parts in all of the figures, 1 indicates the operator's handle which is welded to the fore part of the main beam, said beam being indicated by 2. 3 designates the rear section of the main beam which has a coupling plate welded thereto. The plate 4 has hinged eye bolts 5 and nuts indicated by 6 and dowel pins indicated by 9.

The beam 2 carries a similar coupling plate 7 which is slotted at 8 to receive one of the bolts 5 of plate 4 and has an aperture 41 to receive 55 the other bolt 5, also plate 7 had indications 9

to receive the dowel pins 6, in plate 4. These coupling plates allow the device to be readily taken apart for carrying. In practice the eye bolt 5 which passes through the aperture 41 is merely loosened thus allowing the two parts of the device to be hinged folded. Mid-way of the beam 2 is located a lug 10 which serves as a pivot for the beam. The lug 10 operates within the sleeve 12 and is held in place by pin 11. The sleeve 12 is pivoted at 13 on the arm 14.

14 is a part of the bracket 15 which is secured to the boat 17, by a clamp screw 16. An arm 18 extends from the sleeve 12 and allows for the raising or lowering of the device by means of the adjusting screw 19. The reversing mechanism is controlled from the boat by means of a rod 20 attached to a handle 21 which is pivoted at 22. A spring clasp 23 is provided to hold the handle 21 in place. The beam 3 has welded to one end a sleeve 24 within which another sleeve 29 operates. The reversing mechanism consists of a plate having two arms, one of which extends in the same direction as the beam and the other at right angles thereto. The one indicated by 28 has a stud 30 to which the spring 31 is attached, the other arm is indicated by 34 and has the rod 20 attached thereto.

The parts 28, 29, 30 and 34 can be made in one piece. The propeller blade 25 has a shaft 26 which is notched at 27. The bar 36 which is secured to the propeller shaft 26 by a bolt 35 serves to limit the stroke by reason of the fact that 36 can only move the distance between the adjustment screws 37. The adjustment screws 37 are adjustable within the up-turned ends of the bracket 40.

The spring 31 is attached to the stud 30 at one end and to the link 32 at the other end. The link 32 is swivelly connected to the bar 36 by the stud 33. The stud 33 is shown in detail and has a grease duct 45 therein. The two grease cups are indicated by 38 and 39. A spring 43 is provided to keep the beam in a straight line behind the boat and is attached to the beam 2 by a stud 44 and to the sleeve 12 by a stud 42. The device is operated by a person seated in the stern of the boat who grasps the handle 1 and moves it back and forth. This action causes the propeller blade to move back and forth in the water with a motion similar to that made by the tail of a swimming fish. The propeller blade is reversed by raising the reversing handle 21 up and out of the clasp 23 past the center of the beam and then forced downwardly until the arm 34 is all the way over to the opposite side.

The handle 21 is then clamped down into the clasp 23. The spring 31 serves to keep the propeller in a straight line with the beam and the spring 43 serves to keep the beam in a straight line with the boat thus acting as a rudder when the boat is drifting with the wind.

The spring 31 also acts to bring the propeller blade around in line with the beam so that the return stroke begins without loss of motion.

10 Since all of the working parts except the propeller blade are above water, very little effort is lost. The top of the propeller blade, working about two inches below the surface of the water with a stroke of about 15° past center each way, 15 noiselessly propels the boat at a fair gait.

What I claim is:

1. In a fish-tail propeller, a support, means to mount said support over the end of a boat, a beam pivotally mounted in said support on a vertical 20 axis, one end of said beam extending into the boat and the other end extending to the rear of the boat and carrying a vertical sleeve, a propeller blade having a shaft pivotally journaled in said sleeve, a lever journaled on an axis coincident with that of said propeller's shaft, resilient means connecting said lever with said propeller blade's shaft and continuously tending to maintain the propeller blade in line with said beam.

2. In a fish-tail propeller, a support, means to 30 mount said support over the end of a boat, a beam pivotally mounted in said support on a vertical axis, one end of said beam extending into the boat and the other end extending to the rear of the boat and carrying a vertical sleeve, a propeller blade having a shaft pivotally journaled in said sleeve, a bell-crank lever journaled on an axis coincident with that of said propeller's shaft, resilient means connecting said bell-crank lever with said propeller blade's shaft and continuously tending to maintain the propeller blade in line with said beam.

3. In a fish-tail propeller, a support, means to 40 mount said support over the end of a boat, a beam pivotally mounted in said support on a vertical axis, one end of said beam extending into the boat and the other end extending to the rear of the boat and carrying a vertical sleeve, a propeller blade having a shaft pivotally journaled in said sleeve, a lever journaled on an axis coincident with that of said propeller's shaft, resilient means connecting said lever with said propeller blade's shaft and continuously tending to maintain the propeller blade in line with said beam and means to turn said lever through an arc of 180° to reverse the position of said propeller blade.

4. In a fish-tail propeller, a support, means to 50 mount said support over the end of a boat, a beam pivotally mounted in said support on a vertical axis, one end of said beam extending into the boat and the other end extending to the rear of the boat and carrying a vertical sleeve, a propeller blade having a shaft pivotally journaled in said sleeve, a bell-crank lever journaled on an axis coincident with that of said propeller's shaft, resilient means connecting said bell-crank lever with said propeller blade's shaft and continuously tending to maintain the propeller blade in line with said beam and means to turn said lever through an arc of 180° to reverse the position of said propeller blade.

5. In a fish-tail propeller, a support, means to 60 mount said support over the end of a boat, a beam pivotally mounted in said support on a vertical axis, one end of said beam extending into the boat and the other end extending to the rear of the boat and carrying a vertical sleeve, a propeller blade having a shaft pivotally journaled in said sleeve, a lever journaled on an axis coincident with that of said propeller's shaft, an arm secured at one end to said propeller blade's shaft, a spring connecting the other end of said arm to said lever in virtue of which said propeller blade may swing on its pivot against the action of said spring.

the rear of the boat and carrying a vertical sleeve, a propeller blade having a shaft pivotally journaled in said sleeve, a lever journaled on an axis coincident with that of said propeller's shaft, resilient means connecting said lever with said propeller blade's shaft and continuously tending to maintain the propeller blade in line with said beam and means to limit the movement of said propeller blade in opposition to the maintaining tendency of said resilient means. 5

6. In a fish-tail propeller, a support, means to 10 mount said support over the end of a boat, a beam pivotally mounted in said support on a vertical axis, one end of said beam extending into the boat and the other end extending to the rear of the boat and carrying a vertical sleeve, a propeller blade having a shaft pivotally journaled in said sleeve, a bell-crank lever journaled on an axis coincident with that of said propeller's shaft, resilient means connecting said bell-crank lever with 15 said propeller blade's shaft and continuously tending to maintain the propeller blade in line with said beam and means to limit the movement of said propeller blade in opposition to the maintaining tendency of said resilient means. 20

7. In a fish-tail propeller, a support, means to 25 mount said support over the end of a boat, a beam pivotally mounted in said support on a vertical axis, one end of said beam extending into the boat and the other end extending to the rear of the boat and carrying a vertical sleeve, a propeller blade having a shaft pivotally journaled in said sleeve, a lever journaled on an axis coincident with that of said propeller's shaft, resilient means connecting said lever with said propeller blade's 30 shaft and continuously tending to maintain the propeller blade in line with said beam and means to turn said lever through an arc of 180° to reverse the position of said propeller blade and means to limit the movement of said propeller blade in 35 opposition to the maintaining tendency of said resilient means.

8. In a fish-tail propeller, a support, means to 40 mount said support over the end of a boat, a beam pivotally mounted in said support on a vertical axis, one end of said beam extending into the boat and the other end extending to the rear of the boat and carrying a vertical sleeve, a propeller blade having a shaft pivotally journaled in said sleeve, a bell-crank lever journaled on an axis coincident with that of said propeller's shaft, resilient means connecting said bell-crank lever with said propeller blade's shaft and continuously tending to maintain the propeller blade in line with said beam and means to turn said lever through an arc of 180° to reverse the position of said propeller blade, and means to limit the movement of said propeller blade in opposition to the maintaining tendency of said resilient means. 45

9. In a fish-tail propeller, a support, means to 50 mount said support over the end of a boat, a beam pivotally mounted in said support on a vertical axis, one end of said beam extending into the boat and the other end extending to the rear of the boat and carrying a vertical sleeve, a propeller blade having a shaft pivotally journaled in said sleeve, a lever journaled on an axis coincident with that of said propeller's shaft, an arm secured at one end to said propeller blade's shaft, a spring connecting the other end of said arm to said lever in virtue of which said propeller blade may swing on its pivot against the action of said spring. 55

10. In a fish-tail propeller, a support, means to 60 mount said support over the end of a boat, a beam pivotally mounted in said support on a vertical axis, one end of said beam extending into the boat and the other end extending to the rear of the boat and carrying a vertical sleeve, a propeller blade having a shaft pivotally journaled in said sleeve, a lever journaled on an axis coincident with that of said propeller's shaft, an arm secured at one end to said propeller blade's shaft, a spring connecting the other end of said arm to said lever in 65 virtue of which said propeller blade may swing on its pivot against the action of said spring. 70

axis, one end of said beam extending into the boat and the other end extending to the rear of the boat and carrying a vertical sleeve, a propeller blade having a shaft pivotally journaled in said sleeve, a lever journaled on an axis coincident with that of said propeller's shaft, an arm secured at one end of said propeller blade's shaft, a spring connecting the other end of said arm to said lever in virtue of which said propeller blade may swing 10 on its pivot against the action of said spring and adjustable means to limit the swing of said propeller on its pivot.

11. In a fish-tail propeller, a support, means to mount said support over the end of a boat, a beam pivotally mounted in said support on a vertical axis, one end of said beam extending into the boat and the other end extending to the rear of the boat and carrying a vertical sleeve, a propeller blade having a shaft pivotally journaled in 20 said sleeve, a lever journaled on an axis coincident with that of said propeller's shaft, an arm secured at one end to said propeller blade's shaft, a spring connecting the other end of said arm to said lever in virtue of which said propeller blade 25 may swing on its pivot against the action of said spring and means to turn said lever through an arc of 180° to reverse the position of said propeller blade.

12. In a fish-tail propeller, a support, means to 30 mount said support over the end of a boat, a beam pivotally mounted in said support on a vertical axis, one end of said beam extending into the boat and the other end extending to the rear of the boat and carrying a vertical sleeve, a propeller 35 blade having a shaft pivotally journaled in said sleeve, a lever journaled on an axis coincident with that of said propeller's shaft, an arm secured at one end of said propeller blade's shaft, a spring connecting the other end of said arm to said lever 40 in virtue of which said propeller blade may swing on its pivot against the action of said spring and adjustable means to limit the swing of said propeller on its pivot and means to turn said lever through an arc of 180° to reverse the position of 45 said propeller blade.

13. In a fish-tail propeller, a support, means to mount said support over the end of a boat, a beam pivotally mounted in said support on a vertical axis, one end of said beam extending into 50 the boat and the other end extending to the rear of the boat and carrying a vertical sleeve, a propeller blade having a shaft pivotally journaled in said sleeve, a lever journaled on an axis coincident with that of said propeller's shaft, an arm 55 secured at one end to said propeller blade's shaft, a spring connecting the other end of said arm to said lever in virtue of which said propeller blade may swing on its pivot against the action of said spring and means to turn said lever through an 60 arc of 180° to reverse the position of said propeller blade, said last named means comprising a rod connected to said lever and extending to the boat and manipulatable by the user, and means to hold the rod and thereby hold the lever in 65 either of its two operative positions.

14. In a fish-tail propeller, a support, means to mount said support over the end of a boat, a beam pivotally mounted in said support on a ver-

tical axis, one end of said beam extending into the boat and the other end extending to the rear of the boat and carrying a vertical sleeve, a propeller blade having a shaft pivotally journaled in said sleeve, a lever journaled on an axis coincident with that of said propeller's shaft, an arm secured at one end of said propeller blade's shaft, a spring connecting the other end of said arm to said lever in virtue of which said propeller blade may swing on its pivot against the action of 10 said spring and adjustable means to limit the swing of said propeller on its pivot and means to turn said lever through an arc of 180° to reverse the position of said propeller blade, said last named means comprising a rod connected 15 to said lever and extending to the boat and manipulatable by the user, and means to hold the rod and thereby hold the lever in either of its two operative positions.

15. In a fish-tail propeller, a support, means to mount said support over the end of a boat, a beam pivotally mounted in said support on a vertical axis, one end of said beam extending into the boat and the other end extending to the rear of the boat and carrying a vertical sleeve, a propeller 20 blade having a shaft pivotally journaled in said sleeve, a lever journaled on an axis coincident with that of said propeller's shaft, resilient means connecting said lever with said propeller blade's shaft and continuously tending to maintain the propeller blade in line with said beam, said beam being comprised of sections detachably coupled together for purposes described.

16. In a fish-tail propeller, a support, means to 25 mount said support over the end of a boat, a beam pivotally mounted in said support on a vertical axis, one end of said beam extending into the boat and the other end extending to the rear of the boat and carrying a vertical sleeve, a propeller 30 blade having a shaft pivotally journaled in said sleeve, a lever journaled on an axis coincident with that of said propeller's shaft, resilient means connecting said lever with said propeller blade's shaft and continuously tending to maintain the propeller blade in line with said beam, 35 said beam comprising a clamp, a vertical sleeve pivotally mounted on the clamp to turn about a horizontal axis, an arm carried by said last named sleeve and an adjusting screw carried by said last named arm for adjusting the position of 40 said last named sleeve and thereby adjusting the position of said propeller blade with respect to the surface of the water.

17. In a fish-tail propeller, a support, means to 45 mount said support over the end of a boat, a beam pivotally mounted in said support on a vertical axis, one end of said beam extending into the boat and the other end extending to the rear of the boat and carrying a vertical sleeve, a propeller 50 blade having a shaft pivotally journaled in said sleeve, a lever journaled on an axis coincident with that of said propeller's shaft, resilient means connecting said lever with said propeller blade's shaft and continuously tending to maintain the propeller blade in line with said beam, 55 and means continuously tending to maintain said beam in a straight line with the boat.

HARRY CLAYTON MARTIN.
